FREE FLEXING SEPARABLE FASTENER

Louis H. Morin, Bronx, N. Y., assignor of one-half
to Davis Marinsky, Bronx, N. Y.

Application September 10, 1943, Serial No. 501,832

9 Claims. (Cl. 24—205)

This invention relates to separable fasteners of the type employing stringers having inter-engaging links or scoops adapted to be coupled and uncoupled by sliders movable along the stringers. More particularly, the invention relates to stringers of the kind defined, employing double action scoops having reduced mounting end portions and coupling end portions sharply tapered or bevelled to provide greater flexibility and bending of the stringers in the different uses thereof. The novel features of the invention will be best understood from the following description when taken together with the accompanying drawing, in which certain embodiments of the invention are disclosed, and in which the separate parts are designated by suitable reference characters in each of the views; and in which:

Fig. 1 is a plan view, showing portions of two stringers with my improved scoop thereon in coupled relationship.

Fig. 2 is a section on the line 2—2 of Fig. 1, showing only one of the stringers; and

Fig. 3 is an end view of a scoop, for example, a view looking in the direction of the arrow 3 of Fig. 2.

In the construction of fasteners of the kind under consideration, it has been the custom to form the mounting end portions of the scoops of a thickness conforming substantially to the thickness of the coupling end portions thereof, aside from projecting knob like members which sometimes prevail at one side of the coupling end portion of the scoops.

With these scoop structures, a limited flexure and bending of the tape is permitted by reason of the fact that the mounting end portions of the scoops, or in other words, that portion of the scoops arranged upon the stringer tapes would limit or check the bending or folding of the tapes. Furthermore, the structure of the coupling ends of the scoops has also limited to some degree this bending or folding of the tapes, even in scoops of the double action type and kind, such as here generally disclosed. Still further, conventional types of stringers have been limited in the horizontal flexure of the stringer in extending them around relatively sharp corners by reason of abutment of the coupling ends of the scoops and the relatively wide mounting end portions employed.

In certain types and uses of fasteners, it is desirable to employ greater flexibility in the stringers to adapt the fastener for uses where relatively sharp bends or corners prevail in the articles in connection with which the fastener is employed, or where the fastener curves in a hori-

5 zontal plane around fairly sharp corners. To accomplish this result, I construct the scoops of the stringers with narrow mounting end portions, thus producing a longer tape between the links or scoops at the stringer edges, and also provide sharply bevelled surfaces on the coupling end portions of the scoops which will facilitate a greater rocking of the scoops one upon the other when flexed either transversely or horizontally. In both of these flexures, the narrower mounting end portions provide the necessary clearance for further relative movement of the coupling portions of the scoops one with respect to the other.

In illustrating one adaptation of my invention, I have shown in the accompanying drawing scoops 5, of the double action type. That is to say, scoops which have coupling end portions 6 of common construction on both upper and lower surfaces to provide universal coupling of the stringers one with respect to the other, as well as universal operation of sliders along the stringers in coupling and uncoupling the same.

The scoops 5 include mounting end portions 7, arranged upon the heads 8 of two stringer tapes 9, 9—*a*. As both stringers are of the same construction, the brief description of one applies to both.

20 The coupling end portions 6 have substantially diamond shaped coupling ends 10 defined by oppositely bevelled surfaces 11 and 12 arranged on both upper and lower sides of the scoops. These bevelled surfaces form at upper and lower sides of the scoops substantially flat diamond shaped surfaces 13, the greatest width of which is substantially common to the width of the mounting ends 7. The bevel surfaces 12 will also form at the outer end of the coupling head 8 a diamond surface 14, note Fig. 3.

25 The surfaces 13 are also in horizontal alignment with the upper and lower surfaces 15 of the mounting end portions 7 of the scoops, and are spaced from the surfaces 15 by notches 16, as will clearly appear in Fig. 2 of the drawing.

30 The bevel surfaces 11 unite with the flat side surfaces 17 of the scoops along the line 18, note Fig. 2, and centrally of this line and of the scoop body are formed rounded knob like projections 18 and 18' on opposite surfaces of the scoop. The knobs 18 and 18' form male coupling portions adapted to enter female coupling portions, apertures or recesses 20 centrally of the diamond shaped heads 8 and of the wider portions of said scoops, as will clearly appear from a consideration of Fig. 2 of the drawing.

35 In the usual construction of double action scoops

of the kind under consideration, the mounting end portions 7 have been formed of a width substantially equal to the greatest width of the diamond shaped coupling heads 6. However, in the present construction, the width of the mounting portion 1 has been reduced to a width substantially equal to the widest part of the diamond shaped surfaces 13, which in the present construction are smaller than those heretofore constructed by virtue of greater tapers to the bevelled surfaces 11 and 12.

By this construction, substantially free corner portions 24 are provided at upper and lower surfaces of the narrow mounting end portion 7 adjacent and outwardly of the beads 8 to provide clearance for swinging movement of the heads 6 in the flat or horizontal bending or curvature of the stringers in the manner partially illustrated in Fig. 1 of the drawing.

Furthermore, the sharper or greater beveling of the surfaces 11 and 12 will provide a sharper folding or bending of the stringers one upon the other in what may be termed the transverse direction, permitting the stringers to take a sharper bend. This is also true by virtue of the greater length of tape between adjacent mounting end portions of the scoops, indicated by the opposed directed arrows 22 of Fig. 1 of the drawing. This greater tape length provides greater flexure in the tape itself, as well as preventing abutment of adjacent scoops.

The present construction of stringers or of the scoops on the stringers is adaptable to the formation of contour fasteners in accordance with the teachings in my prior application Ser. No. 460,364, dated October 1, 1942 which eventuated in Patent 2,345,880, dated April 4, 1944. In this application a wider spacing of the scoops is provided on one stringer to adapt the stringer to the curvature desired. In other words, in addition to the spacing of the scoops, the contour of the more or less diamond heads with the narrow mounting end portions will aid in adapting the fastener to the curvatures required.

Considering the structure of the scoop, particularly from the standpoint of the narrow mounting end portions thereof, and further, from the standpoint of the abrupt or sharp tapering of the coupling ends of the scoops, it will appear that a minimum amount of material is used in the construction of scoops, which results in a material saving in the cost of production.

The diamond shaped heads of the scoops may be said to be formed from angularly disposed walls at opposite sides of the scoops, which walls are tapered in the direction of upper and lower surfaces of the scoops, which results in the formation of the diamond shaped upper and lower surfaces and the diamond shape of the end surface of the scoop. In the coupling engagement between the scoops, the angular walls extending toward the mounting end of the scoop form the engaging surfaces, or the recessed portions between adjacent scoops receiving the diamond shaped heads of the scoops of an opposed stringer. In other words, the greatest width of the diamond head of each scoop is substantially equal to the spacing between the opposed surfaces of the mounting end portions of adjacent scoops. On the other hand, it may be said that the width of the coupling end portion of the scoops adjacent the heads is common to the width of the mounting end portion and substantially equal in thickness to the spacing between the widest points or extremities of the heads of adjacent scoops. The

length of the tape between adjacent surfaces of the mounting end portions of the scoops is substantially twice the width of said end portions.

Scoops of the kind under consideration, may be constructed in any desired manner and from suitable materials and by reason of the fact that opposed surfaces of the scoops are of the same construction, the stringers are adapted to be coupled universally with each other. In making the scoops of die cast materials, such as metal castings or plastic castings, the castings may be formed directly upon the tapes in accordance with known practices in this art.

Having fully described my invention, what I claim as new and desire to secure by Letters Patent is:

1. In separable fasteners employing stringers with scoops spaced longitudinally of the stringers, each scoop of the stringer comprising a mounting end portion and a coupling end portion, opposite side surfaces of the coupling end portion being common to provide universal coupling and uncoupling of a pair of stringers, the coupling end portion having a large head at its outer end, the mounting end portion being of a width substantially one-half the widest width of said head, said head having on opposed sides converging walls forming a reduced coupling portion common in width to that of said mounting portion, said reduced coupling portion having common projecting members on opposed side surfaces thereof, and said head having recesses adapted to receive the projecting members on adjacent scoops of opposed stringers in coupling said stringers together.

2. In separable fasteners employing stringers with scoops spaced longitudinally of the stringers, each scoop of the stringer comprising a mounting end portion and a coupling end portion, opposite side surfaces of the coupling end portion being common to provide universal coupling and uncoupling of a pair of stringers, the coupling end portion having a large head at its outer end, the mounting end portion being of a width substantially one-half the widest width of said head, said head having on opposed sides converging walls forming a reduced coupling portion common in width to that of said mounting portion, said reduced coupling portion having common projection members on opposed side surfaces thereof, said head having recesses adapted to receive the projecting members on adjacent scoops of opposed stringers in coupling said stringers together, the converging walls of one scoop engaging corresponding walls of adjacent scoops of an opposed stringer, when said stringers are coupled, and outer ends of said heads having converging walls forming between the same and opposed surfaces of adjacent scoops of a companion stringer a clearance space for free flexure of the scoops one upon the other.

3. In separable fasteners employing stringers with scoops spaced longitudinally of the stringers, each scoop of the stringer comprising a mounting end portion and a coupling end portion, opposite side surfaces of the coupling end portion being common to provide universal coupling and uncoupling of a pair of stringers, the coupling end portion having a large head at its outer end, the mounting end portion being of a width substantially one-half the widest width of said head, said head having on opposed sides converging walls forming a reduced coupling portion common in width to that of said mounting portion, said reduced coupling portion having

common projecting members on opposed side surfaces thereof, said head having recesses adapted to receive the projecting members on adjacent scoops of opposed stringers in coupling said stringers together, converging walls of one scoop engaging corresponding walls of adjacent scoops of an opposed stringer, when said stringers are coupled, outer ends of said heads having converging walls forming between the same and opposed surfaces of adjacent scoops of a companion stringer a clearance space for free flexure of the scoops one upon the other, and both of said inwardly and outwardly converging walls of each scoop being bevelled in the direction of upper and lower surfaces thereof.

4. In separable fasteners employing stringers with scoops spaced longitudinally of the tapes of the stringers, said scoops having narrow mounting end portions, the narrow end portions of said scoops providing between adjacent surfaces thereof tape lengths substantially equal to twice the width of each mounting end portion, said scoops having coupling ends projecting beyond the tape edge, outer portions of said coupling ends having enlarged apertured heads and projecting coupling members for retaining coupled stringers against lateral and transverse separation, and the entire inner portions of said coupling ends being reduced on opposite surfaces to provide spacings between said inner portions of adjacent scoops common to the spacings between said narrow mounting end portions.

5. In separable fasteners employing stringers, each stringer having scoops spaced longitudinally of one edge thereof, the scoops having mounting end portions and coupling ends projecting beyond the stringer edge, said ends having male and female coupling portions whereby coupled stringers are retained against lateral and transverse separation, the entire part of the coupling end and said mounting end portions being both narrower and materially less in width than the greatest width of the male coupling portion, and the narrow structure of the mounting end portion and said entire inner part of the coupling end of the scoops providing a spacing between opposed surfaces of adjacent scoops on the stringer substantially equal to twice the width of said mounting end portion of each scoop.

6. In separable fastener stringers employing scoops spaced longitudinally of one edge of the tape of each stringer, each scoop comprising a narrow mounting end portion, a part projecting beyond and arranged adjacent the tape edge, an enlarged head at the end of said part, said part in its entirety being of a width equal to the width of the mounting end portion, said head having walls diverging outwardly from the end of said part forming male couplings on opposed surfaces of the scoop, the head and said part forming the coupling end portion of the scoop, other common male and female couplings on the coupling end of the scoop and in alignment with the tape edge, and said last mentioned couplings in combination with said heads being adapted to secure coupled scoops of opposed stringers against lateral and transverse separation.

7. In separable fastener stringers employing scoops spaced longitudinally of one edge of the tape of each stringer, each scoop comprising a narrow mounting end portion, a part projecting beyond and arranged adjacent the tape edge, an

enlarged head at the end of said part, said part in its entirety being of a width equal to the width of the mounting end portion, said head having walls diverging outwardly from the end of said part forming male couplings on opposed surfaces of the scoop, the head and said part forming the coupling end portion of the scoop, other common male and female couplings on the coupling end of the scoop and in alignment with the tape edge, said last mentioned couplings in combination with said heads being adapted to secure coupled scoops of opposed stringers against lateral and transverse separation, and the outwardly flared walls of the head of each scoop being bevelled in the direction of upper and lower surfaces of the scoop.

8. In separable fastener stringers employing scoops spaced longitudinally of one edge of the tape of each stringer, each scoop comprising a narrow mounting end portion, a part projecting beyond and arranged adjacent the tape edge, an enlarged head at the end of said part, said part in its entirety being of a width equal to the width of the mounting end portion, said head having walls diverging outwardly from the end of said part forming male couplings on opposed surfaces of the scoop, the head having walls converging to outer ends thereof, the head and said part forming the coupling end portion of the scoop, other common male and female couplings on the coupling end of the scoop and in alignment with the tape edge, said last mentioned couplings in combination with said heads being adapted to secure coupled scoops of opposed stringers against lateral and transverse separation, and the outwardly converging surfaces of the heads of said scoops in combination with said parts thereof forming recesses between said converging surfaces of the scoops of one stringer and said parts of the scoops of an opposed stringer providing free bending of coupled stringers.

9. In separable fastener stringers employing scoops spaced longitudinally of one edge of the tape of each stringer, each scoop comprising a narrow mounting end portion, a part projecting beyond and arranged adjacent the tape edge, an enlarged head at the end of said part, said part in its entirety being of a width equal to the width of the mounting end portion, said head having walls diverging outwardly from the end of said part forming male couplings on opposed surfaces of the scoop, the head having walls converging to outer ends thereof, said head being tapered in the direction of upper and lower surfaces, thereby providing a maximum thickness centrally of the head in alignment with the tape edge, the head and said part forming the coupling end portion of the scoop, other common male and female couplings on the coupling end of the scoop and in alignment with the tape edge, said last mentioned couplings in combination with said heads being adapted to secure coupled scoops of opposed stringers against lateral and transverse separation, and the outwardly converging surfaces of the heads of said scoops in combination with said parts thereof forming recesses between said converging surfaces of the scoops of one stringer and said parts of the scoops of an opposed stringer providing free bending of coupled stringers.

LOUIS H. MORIN.
